(57) **CLAIM**

The ornamental design for a container handle, as shown and described.

DESCRIPTION

FIG. 1 shows a perspective view of a container handle showing our new design;

FIG. 2 shows a bottom perspective view thereof;

FIG. 3 shows a top plan view thereof;

FIG. 4 shows a bottom plan view thereof;

FIG. 5 shows a right side view thereof;

FIG. 6 shows a left side view thereof;

FIG. 7 shows a front view thereof; and,

FIG. 8 shows a rear view thereof.

The broken lines illustrating a container depict environment and form no part of the claimed design.

1 Claim, 7 Drawing Sheets
